UNITED STATES PATENT OFFICE

FRANK H. HOWLETT, OF OAKLAND, CALIFORNIA, ASSIGNOR TO FRED WOLFSOHN, OF SAN FRANCISCO, CALIFORNIA

PLANER

Application filed November 17, 1928. Serial No. 320,199.

This invention relates to planers, and especially to a small portable planer to be used for shaving or planing plaster casts such as used by orthodontists.

6 The object of the present invention is to generally improve and simplify the construction and operation of planers of the character described; to provide a small power driven portable planer particularly 10 adapted for laboratory use and in which the object to be planed is fed by hand as the planing operation takes place; to provide a planer head having a face through which projects a planer knife and against which 15 face the work is held during the planing operation; to provide an adjustable table disposed in front of the planer to assist in supporting the work during the planing operation; to provide means whereby the table 20 may be angularly positioned and secured with relation to the planer; to provide means for trapping and discharging the shavings or cuttings removed by the planer, so as to prevent contaminating the air in the laboratory with flying plaster dust; and further 25 to provide a planer of the character described which is provided with a scribe whereby the plaster cast may be trimmed with one surface parallel to the occlusal 30 surface of the teeth formed on the cast or impression of the oral cavity.

The planer is shown by way of illustration in the accompanying drawings, in which:

Fig. 1 is a side elevation of the planer,

35 Fig. 2 is a front view of the planer,

Fig. 3 is a detailed view showing the plaster cast in position on the table, ready for planing,

40 Fig. 4 shows a modification of the planer head in which the planer knife is disposed on an angle,

Fig. 5 is a central vertical longitudinal view taken on line V—V, Fig. 6.

45 Fig. 6 is a plan view of the planer,

Fig. 7 is a rear view of the planer head showing the manner of attaching the planer knife thereto.

50 Referring to the drawings in detail, particularly Figs. 1 and 2, A indicates a main base plate or frame upon which is supported

a table B and a planer head C. The rear end of the base is provided with a vertical bracket or extension 2, the upper end of which terminates in lugs 3, the lugs 3 being interspaced, as shown, and they form supports for the upper ends of a pair of standards or cross-head guides 4, the lower ends of which are secured in the base at the point 5.

55 The planer or cross-head C is reciprocally mounted on the guides 4. The planer head 60 consists of a substantially rectangular shackle plate or casting 6, the opposite sides of which are drilled and bushed to permit the guides 4 to extend therethrough. The plate 6 is provided with a horizontally disposed slot 7, and 65 the face of the plate rearwardly of the slot is inclined as indicated at 8, see Fig. 5, to receive and support a planer blade or knife 9. The lower end of the blade is beveled or sharpened, as at 10, and projects a slight distance through the slot 7, the distance being equal to the thickness or depth of the cut desired. The blade may be secured to the rear inclined surface of the planer head or plate 6 70 in any suitable manner, for instance, as here 75 shown by slotting the upper edge of the blade as indicated at 11, and by passing securing bolts therethrough, as indicated at 12. The rear face of the planer head or plate 6 is recessed, as indicated at 13, and the recesses 80 form a shoulder or support for a cover plate 14, which may be secured in any suitable manner, as by screws 15. A chamber 16 is formed between the plate 15 and the forward 85 face of the planer, and this space serves to receive and discharge the shavings and dust removed by the knife.

The base A is provided with an opening 17 in alignment with the lower end of the planer head, and as the planer will, under ordinary 90 conditions, be placed on a table or like support, an opening may be formed therein in register with the opening 17 so that shavings and dust will be discharged therethrough, thereby preventing contamination of the surrounding atmosphere. In fact, dust may be entirely eliminated by moistening or slightly wetting the plaster cast before the shaving operation, as will hereinafter be described.

95 A reciprocal movement is transmitted to 100

the planer head when it is in operation in the following manner. Journalled in the bracket 2 is a shaft 18, which is driven from any suitable source of power through means of a pulley 19 or the like. Formed on the inner end of the shaft 3 is a crank disc 20, and secured thereon is a crank pin 21. Secured at the upper end of the planer head is a pin 22 and connecting the pin 22 and the crank pin 21 is a pitman or connecting rod 23. Hence, when shaft 18 is rotated, a reciprocal movement will be transmitted to the planer head.

The table B, upon which the plaster cast is supported is mounted and secured in the following manner. Formed on the base A are a pair of bearing lugs 24, and extending through said lugs and similar lugs formed on the lower surface of the table is a bearing pin 25. This pin forms a pivotal support for the inner end of the table and the outer end may thus be raised so that the surface of the table may assume any inclined or angular position desired, with relation to the planer head. In most instances the table will assume a horizontal or right angular position with relation to the face of the planer head. In that instance, the free end of the table will be supported by an arm 27 pivotally secured in the base, as at 28. This arm is tilted out of the way of the table to assume the dotted line position indicated at 27a when it is not required. When an angular or inclined position is desired, the free end of the table is supported by means of a link 29. The upper end of the link is pivotally secured, as at 29a, to the lower side of the table. The lower end of the link is slotted, as indicated at 30, and it straddles a clamping screw 31. This screw is supported by, and extends through, two bearing lugs 32 and 33 formed on the base. The link passes between these bearing lugs and is clamped between the same. When the table has been adjusted to a desired angular position the clamping action is obtained by threading the bearing lug 33 and by forming a collar 34 on the screw which engages the outer face of the lug 32, the screw being extended and provided with a head 35 to permit it to be conveniently manipulated.

At 36 a post is shown. This post extends through the table and it is vertically adjusted therein, it being secured by means of a setscrew 37. Extending through the upper end of the post is a scribe 38. This is also adjustable, and is secured by means of a setscrew 39. By longitudinally adjusting the scribe and by vertically adjusting the post, any position desired may be obtained. The purpose of the scribe is to indicate the cut on the plaster cast. One end of the scribe is bent, as indicated at 40, and this may be moved into contact with the occlusal surfaces of the teeth on the plaster cast, thus insuring a parallel cut on the under surface of the cast, shown in Fig. 3.

In Fig. 2 the plane or cutting blade 9 is shown in a horizontal position. By referring to Fig. 4 it will be noted that the slot indicated at 7a may be angularly disposed. In that case, the cutting blade is also angularly disposed, but it is secured in the same manner as previously described. This manner of mounting the blade is preferable, as it produces a sheering cut.

In actual operation, when it is desired to trim a plaster cast such as shown at 45 in Fig. 3, it is only necessary to adjust the table B so that a substantially vertical cut is produced when the cast is moved against the face of the planer. The sides, the front and the rear portion of the cast are then trimmed off, and when this has been accomplished the trimming operation is completed, provided the base surface is substantially parallel with relation to the teeth. On the other hand, if the base surface is not parallel with relation thereto, the cast is turned on end and supported on the surface indicated at 46, and the table is adjusted so that it assumes a right angular position to the face of the planer, this being accomplished by releasing the clamping screw 35 and by swinging the supporting arm 27 into place, as shown in Fig. 5. The plaster cast is then moved against the face of the planer and the base will thus be trimmed off at right angles to the end of the cast.

If the cast is fresh and fairly moist wetting of the plaster cast before trimming is not necessary, but if the plaster is dry it is preferable to wet or moisten it before the trimming operation, as considerable dust is otherwise produced. The dust problem, however, is not serious as the cover plate 15 confines the dust and the shavings to the chamber 16, which in turn discharges through an opening 17 which, as previously stated, is in communication with a receptacle or the like placed beneath the table or support on which the planer as a whole is mounted.

The planing operation is rapid and practically any depth cut may be obtained by adjusting the cutting edge 10 with relation to the face of the planer. The plaster cast is held in the hands of the operator at all times during the planing operation. The cast is of course supported by the table B, but it is held against the face of the planer by the operator. He may thus swing the plaster cast around, and as such may produce rounded surfaces or flat or angular surfaces as desired.

By referring to Fig. 5, it will be noted that the face of the planer head is divided into two sections by the slot through which the planer blade projects. The upper section or face of the planer above the slot projects outwardly a slight distance beyond the lower section of the planer face, the distance being approximately the thickness of the

cut. This is desirable as the work to be trimmed or shaped is held by the operator against the face of the planer head and as such can only be moved against the planer face when this assumes its uppermost position as shown in Fig. 3, and it cannot be moved forwardly until the cut has been completed and the planer again assumes its uppermost position. In other words, the work to be planed is moved forward in a step-by-step movement, each step being equal to the depth or thickness of the cut and the forward movement merely takes place when the uppermost position of the planer is assumed or when the cutting edge of the planer passes upwardly beyond the object or the work being trimmed.

While certain features of the present invention are more or less specifically described, I wish it understood that various changes may be resorted to within the scope of the appended claims, similarly that the materials and finishes of the several parts employed may be such as the manufacturer may decide or varying conditions or uses may demand.

Having thus described my invention, what I claim and desire to secure by Letters Patent is:

1. A device of the character described comprising a planer head having a planer face formed on one side thereof; a knife carried by the planer head and projecting through the planer face; means for transmitting a reciprocal movement to the planer head; a table disposed in front of the planer head to support the work to be planed; a pivotal support for one end of the table; a support for the opposite end of the table normally maintaining the face of the table at right angles to the planer face, and a second support, said second support being adjustable to permit the face of the table to assume different angles with relation to the planer face.

2. A device of the character described comprising a planer head having a planer face formed on one side thereof; a knife carried by the planer head and projecting through the planer face; means for transmitting a reciprocal movement to the planer head; a table disposed in front of the planer head to support the work to be planed; and a scrib- ing tool movable vertically and rotatably with respect to said table.

3. A device for shaving plaster casts comprising a base, guides secured to said base, a planer head slideable on said guides, a crank-shaft, a pitman connecting said planer head with said crank shaft, a plane secured to said planer head, a work table positioned with one edge near the path of travel of said plane, a pivotal mounting means for said table near said adjacent edge, and a rest member pivotally connected to said base, adapted, when in one position, to support said table on a plane

perpendicular to the path of travel of said plane.

4. A device of the character described comprising a planer head having a planer face formed on one side thereof, said planer face having a slot formed therein and having the portion above said slot projecting forwardly of the portion below said slot, a knife carried by the planer head and projecting through the slot, means for reciprocating the planer head and work supporting means adjacent the planer head.

5. In a device of the character described a planer comprising a casting presenting an offset planer surface and having a slot formed in the offset portion, a planer blade projecting through the slot and angularly disposed with relation to the offset planer surface, means for imparting reciprocal movement to the planer and work supporting means adjacent the planer.

6. In a planer head of the character described, a planer face formed on one side thereof, said planer face having two offset surfaces, a slot formed in said planer face between said surfaces and a knife carried by the planer head and extending through said slot, the cutting edge of said knife projecting beyond one of said surfaces and terminating in the same plane as the other surface.
